UNITED STATES PATENT OFFICE.

MARTIN LAURSEN, OF ROCHESTER, MINNESOTA.

SAW-VISE.

SPECIFICATION forming part of Letters Patent No. 757,320, dated April 12, 1904.

Application filed July 8, 1903. Serial No. 164,720. (No model.)

To all whom it may concern:

Be it known that I, MARTIN LAURSEN, a citizen of the United States, residing at Rochester, in the county of Olmsted and State of Minnesota, have invented new and useful Improvements in Saw-Vises, of which the following is a specification.

My invention relates to improvements in saw-vises; and the object of the same is to construct a device of this character which shall be simple in construction and efficient in operation.

The novel construction employed by me in carrying out my invention is fully described and claimed in this specification, and illustrated in the accompanying drawings, forming a part thereof, in which—

Figure 1 is a side elevation of my vise. Fig. 2 is a front elevation thereof.

Like numerals designate like parts in the different views.

The numeral 1 designates a U-shaped member having parallel arms 2 and 3. The arm 2 bears a cross-bar 4, which is shaped to form the fixed jaw of my vise. A bench-clamp 5 is connected to the upper end of the arm 2 and is provided with a set-screw 6 for use in securing the vise to a suitable base or support. A T-shaped member 7, having a slotted stem 8 and a cross-bar 9, is pivoted to the upper end of the arm 3, with the arm 3 fitting within the slot 8^a in the stem. The cross-bar 9 is shaped to form the pivoted jaw of my vise.

It will be noted that the clamping-faces of the parts or jaws 4 and 9 are adapted to engage the saw-blade, held therebetween at points one below the other, to provide thereby for the lessening of the vibration of said saw-blade when operating upon the last named.

Pivoted to the extremities of the slotted stem 8 by its arms 10^a is a yoke-shaped member 10, having a cross-bar 11 connecting the arms 10^a. An aperture 12 is formed in the cross-bar 11 to accommodate a set-screw 13.

A rounded lug formed on the lower end of the arm 3 has an indentation 14 formed in the face thereof to serve as a seat for the inner end of the set-screw 13 to hold it against slipping.

In using my vise the bench 5 is secured to some suitable support by means of the screw 6. The saw to be filed is then inserted between the jaws 4 and 9 and the yoke-shaped clamp 10 turned up until the lower end of the screw 13 engages the indentation 14, after which the screw 13 is tightened to actuate the jaw 9 and clamp the saw.

It should be noted that connecting the clamp as near the jaw as possible makes a very steady vise.

I do not wish to be limited as to details of construction, as these may be modified in many particulars without departing from the spirit of my invention.

Having thus described my invention, what I claim as new, and desire to secure by Letters Patent, is—

A vise of the character described, consisting of a stationary jaw member, a bifurcated movable jaw member pivoted, a short distance below its upper end, to the corresponding end of one arm of said fixed jaw member, said stationary jaw having a projection adjacent the lower end of the removable jaw and a yoke pivoted to the lower ends of the legs of said movable jaw member, and equipped with a binding-screw arranged to bear upon said arm adjacent the projection, whereby, by slightly turning said screw in one direction, said yoke may be moved upward to quickly release or open the jaw members.

In testimony whereof I have hereunto set my hand in presence of two subscribing witnesses.

MARTIN LAURSEN.
